UNITED STATES PATENT OFFICE.

PETER WRIGHT, OF DUDLEY, ENGLAND.

IMPROVEMENT IN VISES.

Specification forming part of Letters Patent No. 38,621, dated May 19, 1863.

To all whom it may concern:

Be it known that I, PETER WRIGHT, of Dudley, in the county of Worcester, in the United Kingdom of Great Britain and Ireland, have invented certain Improvements in the Construction of Parallel Vises; and I do hereby declare that the following is a full and exact description thereof, reference being had to the accompanying drawings, and to the letters of reference marked thereon.

Now, to enable others skilled in the art to make and use my invention, I will proceed to describe its nature, and in what manner the same is to be performed—that is to say: I first construct a slide-box, which may be made of cast or wrought-iron, as shown at letter A, suitable to receive a T-shaped slide-bar. I then forge or stamp the two jaw parts, one of which is made with flanges and slotted in the lower part so as to let the slide-bar pass through into the slide-box, as shown at letter C. It is then made stationary to the slide-box by bolts and nuts. The other jaw is slotted in a similar manner and bolted onto the end of the slide-bar at letter B. The next process is to fit in the box F and pin, which may be done in various ways, but I prefer fixing the box (which contains the female screw) on the top of the slide-box, which is grooved out to receive it at letter D, or instead of a box the female thread may be formed on the stationary side of the vise. The pin is then passed through the eyes of the vise and furnished with an adjustable washer to bring back the movable jaw, as shown at letter E.

Having thus described the nature of my said invention and in what manner the same is to be practically carried out, what I claim, is—

The combination of the slide-box A, the T-shaped bar, and sides or jaws, with the box F, when constructed, arranged, and operated as described.

PETER WRIGHT.
